(57) **CLAIM**

The ornamental design for a churro pet treat, as shown and described.

DESCRIPTION

FIG. 1 is a top, front and right side perspective view of a first embodiment of a churro pet treat according to the new design;

FIG. 2 is a top plan view of the embodiment of FIG. 1; FIG. 3 is a bottom plan view of the embodiment of FIG. 1; FIG. 4 is a front elevation view of the embodiment of FIG. 1;

FIG. 5 is a back elevation view of the embodiment of FIG. 1;

FIG. 6 is a left side elevation view of the embodiment of FIG. 1;

FIG. 7 is a right side elevation view of the embodiment of FIG. 1;

FIG. 8 is a top, front and right side perspective view of a second embodiment of a churro pet treat according to the new design;

FIG. 9 is a top plan view of the embodiment of FIG. 8; FIG. 10 is a bottom plan view of the embodiment of FIG. 8;

FIG. 11 is a front elevation view of the embodiment of FIG. 8;

FIG. 12 is a back elevation view of the embodiment of FIG. 8;

FIG. 13 is a left side elevation view of the embodiment of FIG. 8; and,

FIG. 14 is a right side elevation view of the embodiment of FIG. 8.

The break lines shown in the middle portion of the churro pet treat in FIGS. 8–10, 13 and 14 indicate that the appearance of any portion of the article between the break lines forms no part of the claimed design.

1 Claim, 8 Drawing Sheets
